HAIRCLOTH

Eugène Aimé Constant Alfred Gheysens and Paul
Constant Louis André Gheysens, Iseghem,
Belgium

No Drawing. Application May 6, 1936, Serial
No. 78,194. In Belgium May 8, 1935

2 Claims. (Cl. 154—46)

Our invention relates to a product intended to replace the products known by the name of "tailor's canvas" which are generally woven by means of animal hair or vegetable fibres and which are employed in tailoring as cloth for stiffening certain fabrics.

The object of our invention is to provide a particularly thin product possessing considerable elasticity, while being of a much lower cost price than ordinary hair cloths. Furthermore, the product manufactured according to the invention has the advantage over the cloth employed heretofore of remaining absolutely invariable even when it is subjected to the action of water which, as is well known, generally causes the shrinkage of the cloth usually employed.

According to the invention, the new product substantially comprises the combination of a light cloth, with a thin layer or sheet of vegetable fibres or animal hair which is caused to adhere to the cloth by means of a coating of an elastic material, for example a rubber solution. The term "light cloth" above-mentioned defines a fabric having a low-weave count.

In carrying the invention into practice, the product may comprise either a single layer of cloth of relatively large mesh (i. e., a porous cloth) to which the thin layer of hair is fixed by means of the elastic material, or the new product may comprise two layers of a like cloth with the layer of hair interposed between them. The two layers of cloth and the layer of hair are held together by the layer of elastic material serving as a binder. Finally, according to a modification of the invention, the product may even comprise, if desired, a single layer or thin sheet of fibres or hair, the individual elements of which have been made adherent by the elastic material applied under pressure.

Whatever may be the method of working adopted for causing the fibres or hair to adhere either to the cloth, serving as their support or to adhere directly together, the product obtained is finally dried and vulcanised, in order to confer upon the adhesive material, rubber for example, its elasticity and invariability.

By way of example, there will be described in detail hereinafter a method of carrying out the invention in the case of a product comprising a single layer of cloth serving as support for the hair (animal hair or vegetable fibres) fixed to the said support by means of the elastic material.

In this case, the process may be carried out as follows:

The cloth forming the support is unrolled on to a table.

After having suitably fixed the said cloth to the table, there is spread upon it, in a thin sheet, a fine shower of hair, for example by means of a sieve which has a reciprocatory movement and which is displaced above the table. The cloth thus covered with the thin sheet of hair is then coated with the elastic material, for example, latex, either by means of a spraying device or a gumming roller moving over the table. When the cloth covered with hair has been sufficiently coated, it is slightly dried in the air and is then passed through a calender which brings it to the desired thickness. The product thus obtained is then finally subjected to the operation of vulcanisation.

A similar process may be employed in the case in which the product comprises two layers of cloth with a layer of hair inserted between them. In this case, it is merely necessary to apply the second cloth to the first, after the same has been coated with hair in the manner specified hereinbefore, such application being effected before the passage through the calender.

It is obvious however that it is possible to obtain a product consisting merely of a thin sheet of rubber or latex in which the hair is incorporated. Such product, which is similar both from the point of view of its constitution and its properties, may be obtained by spreading the hair or fibres directly on a suitable surface coated with latex or rubber and then subjecting the whole to pressure in order to ensure the cohesion of the interlaced fibres and to form on the supporting surface a product constituted by a film-like layer of rubber containing the hair and adapted to be subsequently separated from its support in order to be passed through a calender, dried and then vulcanised.

In the process above-described in which cloth is used as a support, the cloth, instead of being stationary, may likewise be unrolled below a sieve whence it receives a thin layer of fibre, then it passes under the sprayers which coat it with elastic material and afterwards through the calender which brings it to the desired thickness.

Experience has shown that the product thus obtained constitutes a fine cloth or sheet of extreme flexibility which cannot shrink under the influence of water and which consequently may be employed advantageously in place of the ordinary haircloth known as "tailor's canvas".

What we claim is:

1. A porous hair-cloth resilient in all directions

and adapted for use by tailors, composed of a sheet of textile fabric having disposed thereon a thin layer of resilient hair **promiscuously scattered** in all directions and spaced droplets of latex 5 securing the individual hairs to one another and to the fabric and serving to oppose the tendency of the hair to work itself through the cloth.

2. A porous hair-cloth resilient in all directions and adapted for use by tailors, composed of exterior sheets of textile fabric having disposed therebetween a thin layer of resilient hair pro-

miscuously scattered in all directions and spaced droplets of latex serving to secure the exterior sheets of cloth together and to bind the individual hairs to one another so as to oppose the tendency of the hair to work itself through the cloth. 5
